SPECTACLE FRAME FRONT

John F. Ahern, Chelmsford, Mass., assignor to American
Optical Corporation, Southbridge, Mass.

Filed June 24, 1971, Ser. No. 156,591

Term of patent 14 years

Int. Cl. D16—06

U.S. Cl. D57—1 F

FIG. 1

FIG. 2

FIG. 3

FIG. 4

FIG. 1 is a front elevational view of a spectacle frame front embodying my new design;

FIG. 2 is a top plan view thereof;

FIG. 3 is a side elevational view thereof the opposite side having substantially the same appearance; and

FIG. 4 is a rear perspective view thereof.

I claim:

The ornamental design for a spectacle frame front, as shown and described.
